UNITED STATES PATENT OFFICE.

ALBERT HEYMAN AND CHARLES C. VERVOORT, OF BROOKLYN, NEW YORK.

COMPENSATING SAFETY CLOTHESLINE-HANGER.

1,360,951.

Specification of Letters Patent. Patented Nov. 30, 1920.

Application filed August 1, 1919. Serial No. 314,629.

To all whom it may concern:

Be it known that we, ALBERT HEYMAN and CHARLES C. VERVOORT, both citizens of the United States, and residents of the city of 5 New York, borough of Brooklyn, county of Kings, State of New York, have invented a new and Improved Compensating Safety Clothesline-Hanger, of which the following is a full, clear and exact description.

10 This invention relates to an improved clothes line hanger or support, and relates particularly to the type of hanger which may be withdrawn within a window, so that clothes may be conveniently hung 15 thereon.

While it is not broadly new to provide a clothes line hanger which may be withdrawn within a window, so that the clothes may be conveniently hung on the line, the 20 devices provided have necessitated the use of many parts, and the use of catches for holding the various parts of the hanger in position. Further, in the clothes hangers heretofore suggested, a construction has not 25 been provided in which one end of each of the arms has been carried at a fixed pivotal point, and permit them to be moved from a locked position within the window, when the arms would form an acute angle, 30 through a right angle position, to a position outside of the window when the arms would be substantially parallel.

One of the objects of this invention is to provide an improved clothes line hanger or 35 support, having an endless line, which support is adapted to be moved inward of an opened window, so that the clothes may be readily hung upon the line, thus eliminating the necessity for a person having to 40 reach outward of the window.

Another object of this invention is to provide a clothes line support of simple and rugged construction which is adapted to be positioned outside of the window when 45 not in use, and to be swung inside the window when in use, the said support being of such a construction that it is readily adjusted to windows of different sizes.

A further object of this invention is to 50 provide a compensating safety clothes line hanger which will maintain a relatively constant tension in a clothes line when moved outside a window.

Still a further object of this invention is 55 to provide a compensating safety clothes line hanger requiring but little force to

move the same, the parts of the support being so arranged as to prevent the possibility of the support collapsing when in use.

Still another object of this invention is to 60 provide a compensating safety clothes line hanger of the above type having its parts so arranged that when moved inside a window, the said parts will automatically lock, without the necessity for the use of 65 catches or locking members of any kind.

The above objects are accomplished by providing a clothes line support comprising; a plurality of arms, one end of each of said arms being pivotally mounted at 70 fixed points outside and on opposite sides of a window, a pulley being mounted at the other end of one of the arms to guide a clothes line thereover, the end of the second arm being held in sliding engagement with 75 the first arm, and provided with a plurality of pulleys to guide the clothes line thereover leading to and from the pulleys mounted on the first arm.

The arms are arranged, and the relative 80 lengths of the arms are so proportioned that when the hanger is outside of the window, the arms are substantially parallel and are held in a locked position. To move the end of the arms within the window so that access may be had to the clothes line, the arms are moved relative to each other so that the angular relation between the arms will change from an obtuse angle to an acute angle, the latter being the angular relation 85 of the arms when they are inside the window, and in a locked position. By such an arrangement, it is seen that the arms are moved through what may be termed a dead center position so that a toggle lockjoint is 90 formed. It is the particular arrangement 95 of the arms as above noted which enables the use of independent mechanical locking catches or means, to be dispensed with.

Other objects and advantages will be apparent from the following description and the accompanying drawings, in which similar reference characters designate like parts, in the several views.

In the drawings showing one of the preferred forms of the invention,

Figure 1; is a plan view showing the application of the clothes line hanger to a window, the arms in full line showing the position thereof when drawn inside the window, 110 the dotted lines showing the position of the arms outside of the window.

Fig. 2; is a broken perspective view showing more clearly the relative arrangement of the pulleys mounted on the arms, and the line guided thereover.

5 Fig. 3; is a broken elevation view partly in section showing the end of the forked arm, and the means for holding same in sliding engagement with the other arm.

10 Fig. 4; is a diagrammatic view showing the position of the support when inside and outside of the window, when connected with a clothes line from without.

15 Fig. 5; is an elevation view showing the position of the arms of the support and the clothes line thereon when moved outside of the window.

In the drawings showing one of the preferred forms of the invention, the support comprises two arms, a compensating arm 1 20 and a guide arm 2. One end 3 of the compensating arm is pivotally mounted on a fixed bracket 4 at one side of a window sill 5, outside of a window shown as comprising the frames 6-7. One end 8 of the guide arm 2, is also pivoted or hinged on a fixed bracket 9 mounted on the other side 10 of the window sill. Any suitable brackets may be employed for hingedly supporting one end of each of the arms, but preferably a bracket 25 is provided which may be used interchangeably on either side of the window sill as in the preferred form. The compensating arm 1 is shown as comprising an arm having an I beam construction, the projecting web portion of the I beam being cut away on one side, at one end of the arm, so as to engage a plate 11. A dowel 12 is secured to one end of the plates, the ends of the dowel extending beyond the sides of plate, and being pivotally 30 carried by the spaced brackets 4. The plate 11 is provided with a series of openings 13, so that the length of the compensating arm 1 may be adjusted by connecting the said arm to the plate 11 through the spaced openings 35 by any suitable means, such as a bolt 14. It is understood that any desired construction may be used for arms 1 and 2 and that any suitable means may be provided for adjusting the length of said arms. As shown 40 in Fig. 5 the pivoted end 8 of the arm 2, is preferably of an L shape and is provided with a dowel 15 the ends of which extend beyond the arm, and are pivotally carried in brackets 9. A pulley 16 is rotatably carried at the end of the arm 2, to guide a clothes line 17 thereover. A guard 18 is arranged at the end of the arm 2 around a part of the pulley 16, to prevent the accidental displacement of the line 17 on the pulley 16. 45 The end 19 of the arm 1 is forked forming fingers 20 and 21 spaced so as to receive the arm 2 therebetween. Pulleys 22 and 23 are rotatably supported on a shaft 22' extending through the fingers 20 and 21 respectively 50 of the forked portion of the arm, the said

pulleys serving as guides for the line 17 leading to and from a pulley 16. The outer end of each of the forked arms is closed by a guard 24 and 25 to prevent the displacement of the line 17 from the pulleys 22 and 70 23. The inner wall of the fingers 21 and 22 of the forked end of the arm, extends beyond the guards 24 and 25 forming a stop 26-27, which abuts against a disk portion 28, of the guard 18 for the pulley 16, to limit the relative movement of the arms 1-2 when moved inward of the window. There is provided a means for holding the end of the arm 1, in sliding engagement with the arm 2, so that the pulleys 22 and 23 will act as a 80 guide for the line 17 throughout substantially the length of the arm 2, and further, so that a relatively even tension will be maintained in the line 17, as the arms 1 and 2 are moved outward of the window. 85 When the arm 1 is moved about its pivotal point of support 8 outward of the window, the line 17, passing over the pulley 16 at the ends of the arm, would become slack if there were no means provided to compensate 90 for the same, as for instance the compensating arm arranged as shown in the drawing. Any suitable means may be provided for holding the end of the compensating arm 1 in sliding engagement with the arm 2, 95 but in the preferred form shown, there is provided a plurality of rollers 29 and 30, arranged on opposite sides of the arm 2, and connected by suitable links 31 and 32. One of the rollers 29, and one end of each of 100 the links 31 and 32, is rotatably mounted on the shaft 22'. It is thus seen that as the compensating arm 1 is moved about its point of pivotal support outward of the window, the forked end 19 of the arm is held in 105 sliding engagement with the arm 2, throughout substantially the entire length thereof, and serves as before stated, to guide the line 17, and to take up the slack therein. When the arms are moved outward of the 110 window as indicated by the position of the arms shown in dotted line in Fig. 1, it is seen that further movement of the arm 1 is prevented by the links 31 and 32 connecting the rollers 29 and 30 positioned on the 115 opposite sides of the arm 2. An important feature in the arrangement is that no movable or independent stops or catches are required to securely hold the line support in position either within or without the window. 120

If the line support occupies a position as shown in the full line position in Fig. 1, and it is desired to move the arms to the dotted position as shown in Fig. 1, it is to be noted that the arm 1 will be moved about its point 125 of pivotal support, and the end of arm 1 will be moved along arm 2, moving the said arm 2 to the right a certain distance, changing the angularity between the arm 1-2 from an acute angle, which is the position occu- 130

pied as shown in the full line position in Fig. 1, to a position in which the compensating arm 1 will be normal to arm 2. The arm 2, will continue to move to the right, or 5 anticlockwise about its pivotal point of support, until arm 1 is normal to the said arm 2. Further movement in the same direction of the compensating arm 1, will form an obtuse angle between the arm 1 and 2, and will 10 then permit the arm 2 to move toward the left, or in a clockwise direction, which movement will continue until the arms have assumed a position as indicated by the dotted line in Fig. 1, in which position the arms 15 are substantially parallel. It is to be observed that in moving the arms from one extreme position to the other, that they pass through what may be termed a dead center position. If it is assumed that the arms 20 are moved from a position outside the window as shown in the dotted line position, to a position inside the window as shown by the full line position in Fig. 1, after the arms have reached that position, in which one 25 arm is at right angles to the other, further movement of the arms will form an acute angle between the arms. It is now to be observed that the arms are in a self locking position, so that a force acting upon the line 30 17, in the direction of the arrow, would not tend to cause the arms to collapse. While the arms are held in a locked position, it is to be understood that it takes but little effort to move the arms outward of the window 35 by merely moving the compensating arm 1 outward of the window about its pivoted point.

While the line support has herein been shown as applied to a clothes line, for moving the same inward and outward of a window, to facilitate the hanging of clothes on the line, it is to be understood that the device may be used wherever a line compensating device is applicable.

45 While but one preferred form of the invention has been shown herein it is understood that changes and modifications may be made thereof without departing from the spirit and scope of this invention.

50 Further, while in the preferred construction, pulleys are shown rotatably mounted at the end of the arms 1 and 2 for guiding a line, this invention is not to be limited to such a construction. Any suitable construction or means may be provided which is mounted on or carried by said arms.

Claims:

1. In a clothes line support and hanger, a frame consisting of a pair of members pivotally secured to opposite sides of a window, a fork on the free extremity of one of the members, a pair of superposed sheaves carried in each prong thereof, a sheave on the free end of the other member, and means 65 carried between the prongs of the fork

adapted to embrace the second member to effect simultaneous movement of the same, said sheaves being adapted to engage the line for supporting the same.

2. A support and hanger for endless 70 clothes lines, comprising an arm adapted to be pivoted to one side of a window frame, said arm having a fork on the free end thereof, a second arm adapted to be pivoted to the opposite side of a window frame in 75 alinement with the first named arm and movably confined in the fork, sheaves carried by the fork over which the upper and lower leads of the line are respectively trained, and a sheave carried by the free 80 extremity of the second arm over which the line is trained.

3. A pulley clothes line support and hanger, comprising an arm pivoted to one side of a window, said arm provided with a 85 fork on the outer end thereof, and another arm pivoted to the opposite side of said window in alinement with the first named arm and movably confined in the fork, pulleys carried in the fork over which the upper and lower leads of the line are respectively trained, and a pulley carried by the free 90 end of the second arm over which the line is trained.

4. In a support for endless clothes lines, 95 a pair of arms adapted to be respectively pivoted to the opposite side rails of a window frame for horizontal swinging movements, one of said arms having its free end bifurcated, a yoke pivoted between the furcations thereof for embracing and sliding engagement with the other arm, the said furcations each having slotted portions, a sheave mounted in each of said slotted portions over which the leads of the line are 100 respectively trained, and a sheave mounted in the free extremity of the latter arm over which the inner loop of the rope is trained.

5. A support and hanger for endless clothes lines comprising a pair of arms respectively pivoted to opposite sides of a window for horizontal swinging movements, a vertical pulley mounted in the free extremity of one arm over which the line is trained, a pair of superposed horizontal pulleys carried by the free extremity of the other arm over which the upper and lower leads of the line are respectively trained, and means carried by the free end of said latter arm adapted to co-act with the other 110 arm to effect simultaneous movements of the 115 said arm.

6. In a pulley clothes line support and hanger, an arm adapted to be pivoted to one side of a window having a pulley mounted 125 in its free end over which the inner bight of the line is trained, a second arm pivoted to the opposite side of the window in alinement with the first arm, means on the free end of the second arm adapted to embrace 130

the first arm and the respective leads of the line for guiding said arm and the line in their movements.

7. A pulley clothes line support and hanger, comprising a pair of arms respectively pivoted to opposite outer sides of a window and adapted to be normally arranged with their free ends in overlapping relation exteriorly of the window, a pulley carried by the free end of one arm over

which the line is trained, means carried by the free end of the other arm adapted to slidably couple the same with the first arm and means carried by the second arm adapted to embrace and guide the upper and lower leads of the line respectively to hold the same taut irrespective of the position of said arm. 15

ALBERT HEYMAN.

CHARLES C. VERVOORT.
